US00D861041S

(12) **United States Design Patent** (10) Patent No.: **US D861,041 S**
(45) Date of Patent: ** Sep. 24, 2019

(54) **FLUID PRESSURE CYLINDER**

(71) Applicant: **SMC CORPORATION**, Tokyo (JP)

(72) Inventor: **Ryosuke Morita**, Moriya (JP)

(73) Assignee: **SMC CORPORATION**, Tokyo (JP)

(**) Term: **15 Years**

(21) Appl. No.: **29/608,922**

(22) Filed: **Jun. 27, 2017**

(30) **Foreign Application Priority Data**

Dec. 28, 2016 (CN) 2016 3 0653395

(51) **LOC (12) Cl.** **15-03**

(52) **U.S. Cl.**

USPC **D15/7**

(58) **Field of Classification Search**

USPC D15/7-9; D23/231, 232, 225, 233

CPC F02M 37/04; F02M 31/14; F04D 29/4286

See application file for complete search history.

(57) **CLAIM**

The ornamental design for a fluid pressure cylinder, as shown.

DESCRIPTION

FIG. 1 is a front, top and left side perspective view of a fluid pressure cylinder showing a first embodiment of my new design;

FIG. 2 is a rear, bottom and right side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is a front, top and left side perspective view of a fluid pressure cylinder showing a second embodiment of my new design;

FIG. 10 is a rear, bottom and right side perspective view thereof;

FIG. 11 is a front view thereof;

FIG. 12 is a rear view thereof;

FIG. 13 is a top plan view thereof;

FIG. 14 is a bottom plan view thereof;

FIG. 15 is a left side view thereof;

FIG. 16 is a right side view thereof;

FIG. 17 is a front, top and left side perspective view of a fluid pressure cylinder showing a third embodiment of my new design;

FIG. 18 is a rear, bottom and right side perspective view thereof;

FIG. 19 is a front view thereof;

FIG. 20 is a rear view thereof;

FIG. 21 is a top plan view thereof;

FIG. 22 is a bottom plan view thereof;

FIG. 23 is a left side view thereof; and,

FIG. 24 is a right side view thereof.

1 Claim, 24 Drawing Sheets
